US00D716730S

(12) **United States Design Patent**
Liu et al.

(10) **Patent No.:** US D716,730 S
(45) **Date of Patent:** ** Nov. 4, 2014

(54) **ELECTRONIC BALLAST**

(71) Applicant: **Shenzhen Longgood Intelligent Electric Co., Ltd**, Shenzhen (CN)

(72) Inventors: **Xianwu Liu**, Shenzhen (CN); **Yujie Zhang**, Anhui (CN); **Qingsong Chu**, Hunan (CN); **Jun Ding**, Chibi (CN)

(73) Assignee: **Shenzhen Longgood Intelligent Electric Co., Ltd**, Shenzhen (CN)

(**) Term: **14 Years**

(21) Appl. No.: **29/481,904**

(22) Filed: **Feb. 12, 2014**

(30) **Foreign Application Priority Data**

Jan. 10, 2014 (CN) 2014 3 0007558

(51) **LOC (10) Cl.** 13-02

(52) **U.S. Cl.**

USPC **D13/110**

(58) **Field of Classification Search**

USPC D13/110, 103, 107, 108, 118, 119, 123, D13/133, 137.1, 184, 199; D14/188, 240, D14/251, 356, 432, 433, 434; 174/53, 54, 174/59, 61; 307/11, 150, 151; 320/107, 320/111, 112, 113, 114, 115; 361/679.01; 363/142, 146; 439/131, 172, 626, 628, 439/638

(57) **CLAIM**

The ornamental design for an electronic ballast, as shown and described.

DESCRIPTION

FIG. 1 is a perspective view of an electronic ballast showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

1 Claim, 7 Drawing Sheets

FIG. 2

FIG. 3

FIG. 4

FIG. 5

FIG. 6

FIG. 7
